UNITED STATES PATENT OFFICE

FREDERICK GEORGE CREED, OF CROYDON, ENGLAND, ASSIGNOR TO CREED AND COMPANY LIMITED, A COMPANY OF GREAT BRITAIN

TELEGRAPHIC RECEIVING APPARATUS

Application filed July 22, 1927, Serial No. 207,689, and in Great Britain September 4, 1926.

This invention relates to start-stop telegraphic receiving and printing apparatus working on the five or other multiple unit system, according to which successive groups of signals representing letters or other characters are transmitted to the receiving and printing apparatus which reproduces them as ordinary printed characters, each group of signals comprising a starting signal followed by a number of permutation signals, corresponding to the letter or character, and by a stopping signal. The apparatus comprises a driving shaft, that runs continuously when the apparatus is in operation, and from which a printing wheel is indirectly driven through a clutch, and with which is associated mechanism for selectively positioning the printing wheel so that it shall print ordinary characters corresponding to those represented by successive groups of permutation signals, such mechanism being set in operation by the shaft on the receipt of a starting signal and being afterwards selectively controlled in accordance with the permutation signals to bring about the desired reproduction of the signals in the form of an ordinary printed character. The connection of the said mechanism to the shaft on the receipt of a starting signal and the subsequent control of such mechanism in accordance with the successive permutation signals have heretofore been effected jointly by means herein-after broadly called for brevity and distinction, the controlling means, actuated directly by an electro-magnetic relay worked by the line signals, or by current derived from a local battery and controlled by or from an electro-magnetic relay in the telegraph line, in such a manner that it or they will accurately respond in accordance with the groups of signals received. In either case, the electro-magnetic relay that actuates the controlling means is a power relay and requires a strong current to operate its armature lever from which the controlling means is actuated.

When such a relay is operated direct by line signals, the signal current must therefore be very strong.

The present invention has for its object to enable the controlling means used in telegraphic receiving and printing apparatus of the start-stop kind, for rendering all the several parts of the mechanism successively operative or not operative according to the presence or absence of signals, or according to the character of the signal impulses being received, to be actuated in a better way than heretofore usual, so as to admit of signals being sent, received and dealt with more efficiently than heretofore. A more specific object is to reduce the current required for operating the electro-magnetic relay by means of which the actuation of the controlling means is first initiated and then caused to proceed in accordance with the character of the received impulses, whether such relay be the line relay, or one controlled from the line relay.

For this purpose, according to the invention, there is interposed between the controlling means used in start-stop telegraphic receiving and printing apparatus and the electro-magnetic line relay, or locally energized relay responsive to line signals, a mechanical relay which derives power from the driving motor or member of the receiving apparatus and is under the control of the said electro-magnetic relay, the arrangement being such that the said electro-magnetic relay has only to exert sufficient power to release the output of energy from the mechanical relay to actuate the controlling means.

The mechanical relay can be constructed in various forms but may conveniently be of the type comprising escapement mechanism.

In the accompanying illustrative drawings, Fig. 1 is an end elevation, Fig. 2 a plan and Fig. 3 a side elevation, showing tele-

graphic receiving apparatus of the kind hereinbefore referred to, embodying combined controlling means, a mechanical relay and an electro-magnetic relay according to the present invention. Fig. 4 shows partly in end elevation and partly in section on the line IV—IV of Fig. 5, Fig. 5 in horizontal section on the line V—V of Fig. 4, and Fig. 6 in side elevation, the mechanical relay to a larger scale than in Figs. 1 and 2.

According to the construction of combined controlling means, mechanical relay and electro-magnetic relay shown in the said drawings, the mechanical relay comprises an escapement device one member of which is constituted by a rotary plate 1 that is held by the pressure of a spring 2 in frictional contact with the adjacent end of a cylindrical body 3 arranged to be constantly rotated from the driving member 4 of the receiving apparatus, so that the rotary plate 1 will, when free to do so, be rotated by the said body 3, the rotary plate and body constituting a rotary friction clutch device.

In the example shown, the driving member 4 of the apparatus is a vertical worm driven by an electric motor, not shown, and arranged vertically between and in gear with two worm wheels 5 and 6 fixed respectively to a cam shaft 7 and a printing wheel shaft 8. Attached to shaft 8 is a toothed wheel 9 that is in gear with a toothed wheel 10 fixed to a spindle 11 mounted in a bearing 12 and to one end of which the cylindrical body 3 is fixed. The other member of the escapement device is constituted by two vertical arms 13 and 14 each pivoted at its lower end, one arm, namely 13, being provided at its upper end with a tooth or detent 13^a adapted to engage the upper side of a longitudinal tooth or extension 1^a carried by the rotary plate 1, at the end of one half revolution of such plate, and the upper end of the second arm 14 being provided with a stop 14^a adapted to form an abutment for the said tooth or extension 1^a, at the end of the next half revolution of the said plate. The two pivoted arms 13 and 14 are connected together by a link 15 that is connected by another link 15^a to the armature lever 16 of an electro-magnetic relay 17 which may be the line relay, or a relay controlled by and working in unison with such line relay, for moving the pivoted arms to right or left according as say a positive signal or a negative signal is being received. Fixed to the front side of the rotary plate 1 and journaled on a reduced portion 11^a of the spindle 11 is an eccentric 18 on which is journalled one end 19^a of a rod 19 the other end of which is connected in any suitable manner, as by a lever arm 20, to the controlling means of the receiving apparatus. The spring 2 bears at one end against the outer end of the eccentric 18 and at the other end against a head or collar

21 on the outer end of the portion 11^a of the spindle. As will be understood, each time the escapement plate 1 is released it will be frictionally rotated through half a revolution by the rotating body 3 and its eccentric 18 caused to move the rod 19 and lever 20 to the right or left, according to the nature of the telegraphic signal influencing the relay 17. The rotary plate 1 and cylindrical body 3 forming the friction clutch hereinbefore described, may be replaced by a ratchet, spring or other clutch.

The invention can be applied to combined telegraphic receiving and printing apparatus of various kinds, particularly to apparatus of the start and stop type. It may, for example, advantageously be applied to combined telegraphic receiving and printing apparatus of the start and stop type described in the specification of Patent 1,639,213, to F. G. Creed, and is so applied in the example shown in Figs. 1, 2 and 3. Such apparatus comprises, briefly stated, a series of independently adjustable members 23 adapted to be set in a variable manner to correspond to varying positive and negative signals in a group of signals to be received, representing for example a character, or space, to be reproduced as an ordinary printed character, an adjuster 24 that is adapted to be moved to-and-fro in front of the adjustable members and also towards and from such members, means for moving the adjuster to and fro comprising a rod 25 operated by a lever 26 from a cam 27 on a sleeve 28 adapted to be connected to and disconnected from the constantly rotating cam shaft 7 by a clutch device, as described in the said former specification, means comprising a spring blade 29 forming one arm of a lever the other arm 29^a of which is adapted to be operated by another cam 30 on the sleeve 28 whereby the adjuster 24 can be moved towards each of the adjustable members 23 in turn when brought in front thereof, a spring blade 31 whereby the adjuster 24 can afterwards be moved in a direction away from the adjustable members 23, an electro-magnetic relay responsive to the signals to be received, and means under the control of such electro-magnetic relay, whereby the clutch device can be operated at the required times and whereby the spring blade or arm 29 can be rendered operative or inoperative on the adjuster 24 and consequently on an adjustable member 23, according to the character of the signal being received at the moment when the adjuster is opposite an adjustable member.

The means used in the telegraphic receiving apparatus described in the said specification for rendering the adjuster 24 operative or inoperative on an adjustable member 23, according to the signal being received, and also the means used for actuating the detent or trip device used for controlling the clutch

device between the driving shaft 7 and cam sleeve 28 in such combined receiving and printing apparatus, and which consists of a rock shaft 32 with lever arms constituting in such apparatus what is herein called the controlling means, are actuated from the armature of the said electro-magnetic relay. In such apparatus as modified according to the present invention, the electro-magnetic relay is replaced by a mechanical relay, such as that hereinbefore described, controlled, directly or indirectly by a line relay, and connected as by the eccentric rod 19 and lever arm 20 to the said rock shaft 32, one lever arm 33 of which, in the form of a fork, is used for raising and lowering, in accordance with the signals received, the spring arm 29 of the cam operated lever 29-29^a, forming a hit and miss device for the aforesaid adjuster 24, and another arm 34 (Fig. 3) of which is used for actuating the aforesaid detent or trip device controlling the clutch between the driving shaft 7 of the apparatus and the sleeve 28 carrying the cams used for operating various parts of the combined apparatus.

In other words the printing apparatus of the present application may be said to differ from that of the earlier specification Serial No. 745,935 mainly in that the rock shaft 32 is now moved not directly by the electro-magnetic relay but through the eccentric 18 associated with the clutch of the mechanical relay. When the tooth 1^a of the arm 1 is engaged with either detent 13^a or 14^a due to receipt of a current impulse of one polarity it will remain in engagement with such detent during such time as another like impulse is received and until an impulse of opposite polarity arrives. The movement of the lever arm 29 toward the adjustable members 28 will therefore as before either result or not in the adjuster 24 being engaged.

As will be understood, by using a mechanical relay as hereinbefore described, each time the movable member of the friction clutch forming part of such relay, namely the rotary plate 1 in the example described, is released by the action of the electro-magnetic relay 17, it moves the controlling means, steadily but quickly from one extreme position to the other extreme position and can not oscillate or "chatter" like the armature lever of an electro-magnetic relay is liable to do, so that such mechanical relay is essentially dead beat in action.

What I claim is:—

1. Telegraphic receiving apparatus of the kind herein referred to, comprising signal reproducing means embodying a driving member, clutch escapement means mounted thereon, controlling means for such reproducing means and responsive to said clutch escapement means, an electro-magnet relay responsive to received signals and a mechanical

relay actuated from the driving member aforesaid adapted to operate the controlling means, such mechanical relay being controlled by the electro-magnetic relay which has only to exert sufficient power to release the output of energy from the mechanical relay, substantially as described. 70

2. In telegraphic receiving apparatus of the kind herein referred to, a mechanical relay comprising a rotary member forming part of an escapement device, a rotary driving member and a member to be driven, pivotal members forming a companion part of the escapement device, clutch means mounted adjacent said rotary escapement member and on said driving member whereby the said rotary member is intermittently moved and means movable with the rotary member adapted to transmit motion to the member to be driven, the said escapement having only to exert sufficient power to release the output of energy from the mechanical relay. 80

3. In telegraphic receiving apparatus of the kind herein referred to, a mechanical relay comprising a rotary clutch member forming part of an escapement device, a driven member, a rotary driving member upon which such clutch and escapement member is loosely mounted, pivotal members forming a companion part of the escapement device, a second clutch member operatively secured to the driving member, an eccentric secured to said first named rotary member and a member adapted to be driven by the eccentric, the alternate release and arrest of the rotary member of the escapement device causing the eccentric thereof to move said driven member first in one direction, then to arrest it and afterwards to move the same in the opposite direction and so on in accordance with the electric signals being received. 90

4. In telegraphic receiving apparatus of the kind herein referred to, a mechanical relay comprising a rotary friction clutch member forming part of an escapement device, a rotary driving member upon which such clutch and escapement member is loosely mounted, a driven member, pivotal members forming a companion part of the escapement device, a second friction clutch member operatively secured to the driving member, spring means constantly urging the clutch members into frictional contact with one another, an eccentric secured to said first named relay member and a member adapted to be driven by the eccentric, the alternate release and arrest of the rotary member of the escapement device causing the eccentric thereof to move said driven member first in one direction, then to arrest it and afterwards to move the same in the opposite direction and so on in accordance with the electric signals being received. 100

5. In a telegraph receiving apparatus comprising signal reproducing means, a mechanical relay having a rotatable clutch member, a 110

60

120

125

130

driving member, complementary clutch escapement means loosely mounted on said driving member, an electro-magnetic relay responsive to received signals, complementary pivotally disposed escapement means associated with said clutch escapement and controlling oscillating means adapted to actuate said reproducing means during the engagement of said clutch members in accordance with received electric signals.

Signed at Croydon, in the county of Surrey, England, this seventh day of July, 1927.
